UNITED STATES PATENT OFFICE.

HIRAM S. MAXIM, OF PARIS, FRANCE.

GAS-MOTOR.

SPECIFICATION forming part of Letters Patent No. 293,762, dated February 19, 1884.

Application filed March 9, 1883. (No model.)

To all whom it may concern:

Be it known that I, HIRAM S. MAXIM, a citizen of the United States, at present residing in Paris, in the Republic of France, have invented certain new and useful Improvements in Gas-Motors, of which the following is a specification, reference being had to the drawings accompanying and forming a part of the same.

10 My invention relates, mainly, to gas-motor engines, wherein the gaseous pressure in a cylinder, resulting from the combustion of a mixture of air and an inflammable gas or vapor, is caused to operate a piston and drive a crank-shaft; and it consists, first, in the combination of two working-pistons and two exhaust or vacuum-producing pistons operating together in the same engine under the conditions hereinafter set forth; second, in the combination, with 15 of two sets of cylinders, working and exhaust pistons connected together and operating therein, and two sets of air-inlet, gas-inlet, and exhaust-valves, whereby the engine is rendered double-acting; third, in the combination, with 20 the parts named, of an igniting or exploding device constructed and arranged to explode the gaseous charges in the cylinders alternately; fourth, in the combination, with this or 25 similar engines, of starting devices of novel construction; and, lastly, in details in the construction of the several parts of the engine and appurtenances, the nature of which will be more fully hereinafter described.

In the drawings I have illustrated an engine 30 embodying the several features of my invention, Figure 1 being a plan view of the engine; Fig. 2, a central vertical and longitudinal section of the same; Fig. 3, a horizontal longitudinal section.

40 The engine represented is an improvement on that shown in another application filed by me—viz., No. 82,361—and may be arranged either as a horizontal or vertical engine. The present form being, however, adapted especially for engines of large size, is advantageously mounted on a horizontal base. The several parts of the engine, their purposes and functions, will be described by reference to the drawings.

50 A and A' are the working-pistons, B and B' the exhaust-pistons, or those designed for producing a vacuum in the parts of the cylinder

in which the working-pistons operate. Pistons A, B and A', B' are cast in one piece, the area of pistons B, B' being a little more than 55 double that of the others.

C C' designate the cylinders in which the pistons A and A' work, and D D' the cylinders of greater diameter, in which the exhaust-pistons B, B' operate. The cylinders C C' are 60 separated by a stout head, a, in which is a chamber, a'. The cylinders may be formed independently of one another and the bed-plate E of the engine, or they may be cast in one piece with the bed-plate, the special method of 65 their construction, together with that of other parts of the engine—such as the several supports, conduits for admitting or expelling the air and gas, and the like—being in a measure immaterial to the objects of the present invention. The pistons A, A' are connected by the rod b, that passes through the head a, and to 70 keep this rod from overheating a circulation of water is kept up in the space a' in direct contact with the rod b. As a further precaution against the overheating of the cylinders C C' or any of their parts, they are surrounded by the water-jackets c c.

In the lower part of the cylinders C C', and at their ends, are the air-inlet valves G G', with 80 stems g, that are connected to the ends of a flat spring, g', the force of which is adjusted to allow the proper amount of air to be drawn into the cylinder by the action of the pistons.

On the sides of the cylinders C C' are the 85 gas-inlet valves H H', the stems h of which extend out through the tubes h', and are combined with springs s, that keep the valves H H' closed. The tubes h', communicate with a gas-supply pipe, e, by branch pipes, as shown. 90

Opposite the gas-inlet valves are chambers f f', through which the flame is introduced. For igniting the gaseous mixture in these chambers at the proper intervals, I employ a slide, J, having two chambers, i i', extending through 95 it, from which chambers extend passages l l', leading to smaller chambers, a" b", in the inner face of the slide.

K is a flame-chimney midway between the chambers f f', in which a gas-jet is kept constantly burning. In their normal movement the pistons A, A' are lifted completely out of their respective cylinders into the spaces intervening between the small and large cylin-

ders. In these spaces are set metal rings L L', that serve to hold the pistons A A' in place when they are lifted out of the cylinders and prevent the expansion of their rings. Passages m m' lead from the spaces M M', in which the rings L L' are placed, to exhaust-valves N N', opening into a chamber, n, from which leads an exhaust-pipe, N".

F is the crank-shaft; F', the connecting-rod connecting the crank with the pistons A B.

P is an eccentric on the crank-shaft; P', a rod connecting the eccentric strap with the igniting slide or piston J.

In a wheel, O, on the crank-shaft F, is a roller, o, carried by an arm extending from the hub of the wheel O.

R is a slide or bar mounted in any suitable manner alongside the wheel O, so as to be capable of a horizontal reciprocating movement.

20 On the slide R are two projections, r r', with which the roller o is brought successively in contact by the rotation of wheel O. The slide R is connected by a rod, R', with a double bell-crank lever, t, pivoted between the gas-inlet valves H H' in a position to force one or the other valve open, according to the direction in which it is turned. It is desirable that the roller o be connected with a centrifugal governor of suitable kind, whereby it may be shifted toward or from the slide R as the speed of the engine varies. The projections r r' are beveled or stepped when this is the case, in order that the roller o may open the valves H H' more or less, according to the speed of 35 the engine.

The governor and connections are not shown herein, as they do not enter into the present invention, and are fully shown and described in other applications filed by me.

40 The operation of the engine is as follows: The pistons are moved by turning the crank-shaft F. As one of the pistons—say A—is drawn out of the cylinder C, it draws in air through the valve G; but as the force of spring g prevents valve G opening to its full extent not enough air is drawn in to fill the cylinder, so that a partial vacuum is formed. The piston B at the same time produces a partial vacuum in the cylinder D and space M, so that 45 when the piston A has passed beyond the cylinder C the air passes out freely into the space M and cylinder D, establishing an equilibrium of pressure between the two cylinders. On the backward movement of the pistons the 50 piston A, on entering its cylinder, closes off communication with cylinder D. At this moment the roller o comes into contact with the projection r on slide R and opens the gas-valve H, by which sufficient gas or gas and air should enter the cylinder C to bring the pressure therein to about one atmosphere. The backward movement of the pistons A B compresses the gas in cylinder C until a pressure of about forty pounds is attained. At 55 this moment the piston or slide J has been carried forward sufficiently to bring the chamber i opposite the chamber f, and as on the back-

ward movement of the slide the chamber A" receives a charge of gas which is ignited as it issues from chamber i the application of this 70 flame to the compressed gases in cylinder C causes an explosion which drives the piston A forward. When the latter leaves the cylinder C, the gases in the latter are sucked out and the same action continues. On the back-stroke of the pistons the air and gas in cylinder D is driven out through valve N. While the piston A is driven forward by the explosion of gas in cylinder C, piston A' is drawn backward, compressing the gas admitted 80 through valve H', which was opened by the contact of roller o with the projection r' as the piston A was entering the cylinder C' on its back-stroke. The return of the slide J from igniting the gas in cylinder C brings the chamber i, with its lighted charge of gas, opposite the chamber f' and explodes the charge in cylinder C'. In all respects the further action of pistons A' B' is the same as that of pistons A B, the operations of charging and discharging in each case being alternate. By thus making the engine double acting a large amount of power may be got out of a comparatively small engine, and the speed is much more uniform than in ordinary single acting engines. 95

To start an engine of this kind requires considerable power. It is also necessary to remove the belt or shift it onto a loose pulley before starting heavy machinery. This of course requires the fly-wheel to be made twice 100 as wide as usual in order to give room to run the belt onto a loose pulley. In order to avoid these difficulties I have devised a starting device applicable to this and similar engines, the construction of which I will now explain. 105

On the crank-shaft F is a drum, S, a cog-wheel, S', and a tangent-screw, s', on a shaft, U, turned by a crank, and capable of being dropped away from the cog-wheel S'. Over the drum S runs a cord, V, that runs over a 110 pulley, V', and is then attached to a heavy weight, W. The drum S and cog-wheel S' are loose on the shaft, and may be turned to wind up the weight without turning the crank-shaft. The unwinding of the cord, however, 115 turns the shaft F by a ratchet and pawls contained in the drum, as shown. The fly-wheel F" is loose on the shaft F.

X is a friction-clamp keyed to the end of shaft F, and Z a hand-wheel set in the end of 120 said shaft for loosening or tightening the friction-clamp X against the fly-wheel.

To start the engine the clamp is raised from the fly-wheel by unscrewing the hand-wheel Z. The weight W is then wound up, and the 125 gas-flame having been ignited and the other necessary steps taken, the shaft U is dropped away from the cog-wheel S' by removing a pin, u, which supports one of the bearings of said shaft. The unwinding of the weight W turns 130 the crank-shaft F and moves the pistons, by this means drawing in the charges of gas and starting the engine. When the engine has started, the hand-wheel Z is tightened up, caus-

ing the friction-clamp X to bind against the fly-wheel F", thus imparting the movement of the engine to whatever machinery it may be desired.

5 I have now described the general plan and purpose of my invention. Many minor details of construction that contribute to the more efficient operation of the engine are not described at length, inasmuch as they are in part 10 well understood by those skilled in the art, and in part described and claimed in other applications filed by me. Reserving, therefore, the right to claim in other applications for Letters Patent now on file or about to be made 15 features of novelty shown herein, but not claimed—

What I claim is—

1. In a gas motor or engine operating by explosions of gas or gaseous mixtures, the combination of two working-pistons, two exhaust-pistons, valve mechanism, and igniting devices, all substantially as described, these parts being constructed for operating conjointly as a double-acting engine, as set forth. 20
2. In a gas motor or engine operating by explosions of gas or gaseous mixtures, the combination, with two sets of cylinders placed end to end, of two working and two exhaust pistons connected together and working in said 25 cylinders, valve mechanisms connected with the cylinders, and igniting mechanism operating conjointly as a double-acting engine, as set forth.
30
3. In a double-acting gas-engine, the combination, with two sets of cylinders and connected 35

pistons working therein, of two sets of exhaust-air-inlet and gas-inlet valves, and an igniting mechanism for exploding the charges in the cylinders alternately, as set forth.

4. The combination, with cylinders C C' and 40 connected pistons A A', of valve mechanism for admitting charges of air and gas into the cylinders alternately, mechanism for igniting the charges, and mechanism for withdrawing the products of the combustion of the charges, 45 these parts being constructed and arranged for conjointly operating as a double-acting engine, as set forth.

5. The combination, with the shaft of a gas engine or motor, of a loose belt or fly-wheel, 50 means for locking it to the shaft, and a starting device for imparting a rotary movement to the shaft, as and for the purpose set forth.

6. The combination, with the shaft of a gas engine or motor, of a winding-drum, a cord, 55 and a weight arranged for imparting a rotary movement to the shaft for starting the engine, as set forth.

7. The combination, with the shaft of a gas engine or motor, of a loose belt or fly-wheel, 60 an adjustable friction-clamp, a winding-drum, a cord, and a weight, these parts being constructed to operate as a starting device for the engine, as set forth.

In testimony whereof I have hereunto set 65 my hand this 16th day of February, 1883.

HIRAM S. MAXIM.
